CLEANING DEVICE FOR GLASS-WASHING
MACHINES

Jacob D. Markwood, Minneapolis, Minn.

Original application November 30, 1936, Serial No.
113,411. Divided and this application August
7, 1937, Serial No. 157,922

5 Claims. (Cl. 15—123)

This invention relates generally to apparatus for cleaning and scrubbing drinking glasses, tumblers, steins, cups, and the like, and more particularly to a scrubbing unit or head for use in cleaning the interior surfaces of such vessels.

The main object of this invention is to provide a cleaning unit for this purpose which includes members of sufficient flexibility and pliability so that they will conform to the inner contour of a glass of any usual shape, and will thus contact and clean the entire inner surface of the glass when the unit is inserted thereinto. Another object is to provide a cleaning unit of this kind wherein is embodied a center nozzle or spindle element for conveying a cleaning liquid to the unit and the glass being cleaned, and to which nozzle a plurality of flexible, pliable, and resilient scrubbing elements are affixed in such manner that their margins are left free to flex and fold as may be necessary in order to reach all parts of the interior surface of the glass, and so that these margins will each engage the glass to exert a scrubbing action thereon when the unit is rotated. Another object is to provide a unit of this kind with additional scrubbing and cleaning elements in the form of bristle brushes secured to the aforesaid scrubbing elements between the free margins thereof and with the bristles spread apart in a radiating fashion so as to fill out the space between said margins and present a substantially rounded or cylindrical contour for the unit as a whole. Still a further object is to provide an assembly of this kind wherein one of the flexible scrubbing elements is extended endwise beyond the ends of the remaining elements whereby this extension is free to fold over and partially roll or curl as may be necessary for it to reach the bottom of a very tapered form of glass.

The foregoing and still other and more specific objects will be disclosed in the following detailed specification, reference being had therein to the accompanying drawing, wherein:

Fig. 1 is a side elevation of the cleaning unit, showing the same as mounted on a rotating element for supporting and rotating the unit.

Fig. 2 is an enlarged diametrical section along the line 2—2 of Fig. 1, and showing the unit alone.

Fig. 3 is an enlarged cross section along the line 3—3 in Fig. 1, this view illustrating the action of the unit on the interior of a glass and which glass is also shown in cross section.

It may be noted at this point that the present application is a division of my parent applica-

tion Serial No. 113,411, filed November 30, 1936, for Glass scrubber and sterilizer.

Referring now with more particularity to the drawing, the reference character A designates a portion of a cylinder which has the sleeve B receiving the spindle shaft C held in the sleeve against independent rotation by means of the diametrically extended pin D. The shaft C in use is rotated together with the sleeve B and attached cylinder A, and also this shaft C has the axially extended bore or chamber E through which the cleaning liquid is fed to the cleaning unit. These parts and their operation are set out in detail in the aforesaid copending application, and are shown herein only for convenience in describing the operation of this invention.

The present invention provides a cleaning unit or head including as its main or supporting element the elongated nozzle or spindle 4 having the enlarged socket portion 5 at its intended lower end, and which socket portion is adapted to seat over the sleeve B and be removably retained thereon by means of bayonet notches 6 found in the walls of the socket and engaged with the ends of the pin D as shown in Fig. 1. The nozzle 4 has the axially extended bore 7 which will register with the aforesaid chamber E in the spindle shaft C when the nozzle is mounted as described, and this bore 7 will then conduct the cleaning liquid upwardly from the chamber and allow it to flow downwardly over the cleaning elements affixed to the nozzle, as will hereinafter be apparent.

As evidenced in the drawing, the nozzle 4 is vertically disposed when in use, and the nozzle is given a taper form end to end, with the smaller end turned upwardly so that the unit as a whole will have a corresponding upward taper such as will facilitate its entrance into a glass when the same is inverted and placed down over the unit.

It will be particularly noted in Fig. 3 that the nozzle or spindle 4 is of triangular cross section, and upon the three contiguous vertical faces thus formed are secured three scrubbing elements 8, 9, and 10. These scrubbing elements take the form of flat, flexible, and resilient members which are secured tangentially at their medial portions to the three faces of the nozzle, leaving their opposite lateral margins or wings 11 freely extended as shown. The mounting is by means of plates or strips 12 secured vertically along the centers of the elements 8, 9, and 10, and drawn tight by screws 13 tapped into the nozzle as shown. Due to the triangular shape of the nozzle 50

zle the adjacent free margins **11** of the scrubbing elements **8**, **9**, and **10** will stand out from the nozzle, side by side, in a radial direction relative to the axis of the nozzle.

5 In addition to the flexible scrubbing elements **8**, **9**, and **10** I provide three brush members **14**, **15** and **16**, one of which is mounted lengthwise or vertically along the center of each scrubbing element. These brush members are each made **10** up of bristles carried by a twisted wire **17**, the ends of which are turned inwardly through apertures **18** in the mounting places **12** and anchored thereby, and the bristles radiating from the wires assume a semi-cylindrical formation such as will **15** fill out the spaces between the free margins of the scrubbing members, as evident in Figs. 1 and 3.

In use the cleaning unit is rotated by the shaft **C**, and the cleaning liquid is fed to the top **20** through the nozzle **4** so that it flows down over the various cleaning elements. The glass to be cleaned, indicated at **F** in Fig. 3, is then inverted and placed downwardly over the unit so that the scrubbing elements **8**, **9**, and **10** and the brush members **14**, **15**, and **16** engage and operate against the inner surface of the glass to clean the same. In this operation the free margins or wings **11** of the scrubbing elements **8**, **9**, and **10** will readily flex and bend as may be necessary, **25** and will engage and scrub the entire inner surface of the glass, no matter what its shape or conformation may be, as will be readily apparent. It is an important feature of this invention that, while the said margins **11** normally stand together as stated, they will be spread apart slightly when entered into a glass (see Fig. 3), and will present six separate and distinct scrubbing edges acting on the glass. To facilitate the necessary flexing of the margins **11** they have **30** slits **19** cut at spaced intervals so that the portions between the slits have great freedom of movement. Also an important feature of this invention is the extension of one scrubbing element, as **10**, so that its upper end portion **25** projects above the upper ends of the remaining elements, and is thus free to bend, curl, or fold as may be necessary in order to reach the very bottom of a tapered form of glass.

The brush members **14**, **15**, and **16** of course **50** will flex and bend as necessary to accommodate the glass (Fig. 3), and will add their brushing effect to the scrubbing action of the margins **11** to thoroughly clean the glass in a short time.

It will be noted in Figures 1 and 2 that the **55** brush members **14**, **15** and **16** extend only partially along the length of the scrubbing members **8**, **9**, and **10** and terminate considerably short of the upper end of the assembly. As a result, the upper ends of the scrubbing members are free to **60** flex and fold as may be required to reach the bottom of the glass while the brush members are disposed in position to exert their brushing action mainly adjacent the rim of the glass where most needed.

65 It is understood that suitable modifications of the structure may be made, provided such modi-

fications do not depart from the spirit and scope of the appended claims. Having now therefore fully illustrated and described my invention, what I claim to be new and desire to protect by Letters Patent is:

5 1. A scrubbing device comprising an elongated spindle of triangular cross section, a flat resilient scrubbing member secured by its medial portion longitudinally to each flat face of the spindle and with its sides extended freely from the contiguous corners of the spindle to thereby meet and mutually support the corresponding sides of adjacent scrubbing members in radially extended directions relative to the axis of the spindle.

10 2. A scrubbing device comprising a spindle of multilateral form, a flat resilient scrubbing member mounted flatly by its medial portion along each side of the spindle and extending freely from the adjacent corners of the spindle to meet and support the corresponding free extension of adjacent scrubbing members in radially turned directions relative to the axis of the spindle, mounting members securing the medial portions of the said scrubbing members to the sides of the spindles, and brush bristles secured to the said mounting members and extended in flaring radial directions therefrom between the radially extending portions of the scrubbing members.

15 3. A scrubbing device comprising a supporting and operating member of multilateral form, a **20** flat, pliable scrubbing member mounted by its medial portion along each side of the supporting member and extending at its margins freely from the corners thereof to thereby meet and mutually support the corresponding margins of adjacent scrubbing members in radially extending directions relative to the axis of said supporting member, and brush elements mounted on the flat portions of the scrubbing members with their bristles extended in flaring radial directions between the extended margins of the said **25** scrubbing members.

30 4. A scrubbing device comprising a supporting and operating member of multilateral form, a **35** flat, pliable scrubbing member mounted by its medial portion along each side of the supporting member and extending at its margins freely from the corners thereof to thereby meet and mutually support the corresponding margins of adjacent scrubbing members in radially extending directions relative to the axis of said supporting member, and brush elements mounted on the flat portions of the scrubbing members with their bristles extended in flaring radial directions between the extended margins of the said **40** scrubbing members.

45 4. A scrubbing device comprising a supporting and operating member of multilateral form, a **50** flat, pliable scrubbing member mounted by its medial portion along each side of the supporting member and extending at its margins freely from the corners thereof to thereby meet and mutually support the corresponding margins of adjacent scrubbing members in radially extending directions relative to the axis of said supporting member, and one of the said scrubbing members being extended endwise beyond the others.

55 5. A scrubbing device comprising a supporting and operating member of multilateral form, a **60** flat, pliable scrubbing member mounted by its medial portion along each side of the supporting member and extending at its margins freely from the corners thereof to thereby meet and mutually support the corresponding margins of adjacent scrubbing members in radially extending directions relative to the axis of said supporting member, all of the said scrubbing members being extended at one end freely from the end of the supporting member.

JACOB D. MARKWOOD.
